UNITED STATES PATENT OFFICE.

BENJAMIN E. PANETH, OF NEW YORK, N. Y., ASSIGNOR TO CASPER BLOOMBERG,
OF NEW YORK, N. Y.

GARTER.

No. 873,084.

Specification of Letters Patent.

Patented Feb. 4, 1908.

Application filed July 27, 1907. Serial No. 385,814.

To all whom it may concern:

Be it known that I, BENJAMIN E. PANETH, a citizen of the United States, residing at the city, county, and State of New York, have 5 invented a new and useful Improvement in Garters, of which the following is a specification.

My invention relates primarily to an improvement in the garter shown in the patent to Casper Bloomberg, No. 851,219, dated April 23, 1907.

Among my objects are the production of a garter in which the leg band and depending strap will be integral, to obviate the necessity of making rights and lefts, and to afford a swinging motion to the depending strap on the end of which the sock engaging member is fastened.

In the accompanying drawing Figure 1 is 20 a view of my garter with the ends secured together, Fig. 2 a plan view of the structure of Fig. 1; and Fig. 3 a plan view of the preferred form of the garter.

The garter comprises a leg encircling band 25 1, which is perforated as shown. A suitable two part fastener 2, 3, capable of allowing a rotary motion when engaged, and preferably of the ball and socket type is secured at the ends of the band, the slide part 2 of which 30 can be slid along the band for adjusting purposes.

The depending strap 4 is integral with the band 1 and is located adjacent to one end of it, extending in a line with the fixed or ball member of the fastener. Sock engaging means 5 are secured to the end of the strap 4. The band 1 being straight can be used on either the right or the left leg and when the garter is in use the ball and socket fastening 40 permits a swinging motion of the strap 4 which is in line with it and permits it to hang in a substantially vertical line and to yield with the movements of the wearer thereby increasing his comfort. As the

band and strap are integral there is no undue thickening and bunching at the junction of band, strap and fastening such as would occur if the strap 4 were separate and pivotally secured to the band 1.

As shown in Fig. 3 two depending straps 50 are shown, the second of which is located at a point opposite the end strap 4 when in use and by the use of which the sock can be supported at two points.

I claim:

1. A garter comprising a leg encircling band; an integral strap extending from the band in the same plane and depending therefrom adjacent to one end; both band and strap being formed to shape from a sheet of material without folding; means on the end of the depending strap for engaging the sock; and two part means on the ends of the band for securing it together, one of said parts being adjustably secured to the band 60 and the other fixed thereto in line with the depending strap.

2. A garter comprising a leg encircling band; a plurality of integral straps extending from the band in the same plane and depending therefrom, one of which is adjacent to one end of the band; both band and straps being cut to shape from a sheet of material without folding; means on the ends of said straps for engaging the sock; and two part means on the ends of the band for securing it together, one of said parts being adjustably secured to the band 70 and the other fixed thereto in a line with the depending strap adjacent to the end of the band.

In testimony whereof I have hereunto subscribed my name in the presence of two witnesses.

BENJAMIN E. PANETH.
